UNITED STATES PATENT OFFICE.

GEORGE W. LENNOX, OF HAVERHILL, MASSACHUSETTS.

LEATHER-FINISHING MACHINE.

SPECIFICATION forming part of Letters Patent No. 436,363, dated September 16, 1890.

Application filed November 29, 1889. Serial No. 331,921. (No model.)

To all whom it may concern:

Be it known that I, GEORGE W. LENNOX, of Haverhill, in the county of Essex and State of Massachusetts, have invented a new and Improved Leather-Finishing Machine, of which the following is a specification.

In the finishing of leather for many purposes one surface of the leather is blacked and is then subsequently polished or glazed.

10 This polishing or glazing is done on a glazing-machine which gives to the leather a high luster or glaze which is required in many of the uses to which the leather is put. The leather, however, after being blacked cannot be operated upon directly by the glazing-machine, since the effect of the glazing or polishing operation would be to glaze away or remove the blacking. It is accordingly necessary after blacking the leather and before 15 glazing it to apply a seasoning solution to the leather to prepare it for glazing. The seasoning solution ordinarily employed is a mixture of red aniline dye, blood albumen, extract of logwood, milk, and water. This seasoning solution is applied to the blacked surface of the leather and is thoroughly rubbed in. This seasoning operation sets the black color and enables the leather to take a high 20 polish. The seasoning of the leather has 25 heretofore been ordinarily done by hand.

Now the machine which constitutes the subject-matter of the present invention is one which is particularly adapted and designed for applying the seasoning solution to 30 previously-blacked leather.

In order that the machine may properly apply the seasoning solution to all parts of the surface of the leather and may thoroughly rub the solution into the leather, it is provided with a power-driven padded roller, 35 which rotates in fixed bearings, a source of supply for the solution from which the solution is conveyed to the padded roller, and a universally-movable leather-carrying 40 table or bed which moves to and from the roller, which can be pressed with any desired degree of pressure against the roller, and which enables the surface of the leather to be presented to the action of the roller for as 45 long an interval (or as many times) as may be necessary to thoroughly rub the solution in.

While the primary object of the machine is to apply the seasoning solution to the leather, and while only when used for this object are all of its functions and capabilities utilized, nevertheless it can, if desired, be 55 conveniently used for other purposes in connection with the finishing of leather, and can be used for applying any liquid dressing, mixture, or solution to the surface of the 60 leather for the purposes of blacking, oiling, or otherwise treating the leather.

The invention is illustrated in the accompanying drawings, in which Figure 1 is a front view of the improved machine. Fig. 2 is a plan view. Fig. 3 is a vertical section in a plane indicated by the line 3 3 in Fig. 2. Fig. 4 is a vertical section in a plane indicated by the line 4 4 in Figs. 2 and 3; and Figs. 5 and 6 are views of parts in detail.

The machine comprises as its essential operative parts a constantly-rotating power-driven padded roller A, journaled in fixed bearings, a supply feeding-tank B, containing the solution which is fed to the padded roller, 75 and a universally-moving table or bed C, on which the leather is placed, and by means of which every portion of the surface of the leather may be brought into contact with the padded roller.

By a universally-moving table or bed is meant one which is capable of a movement in three directions, vertically, longitudinally, and laterally.

The universally-moving table or bed is operated by the attendant, and may be moved vertically and horizontally in right lines, and may be revolved in a horizontal plane, which effects the necessary lateral movement.

The universally-moving table or bed C is supported on a suitable frame-work D, having vertical posts E at its four corners, each of which is formed with a vertically-extending groove or way a.

Sliding vertically in the four ways a a in 95 the several posts E E are four vertically-sliding bars F F. These sliding bars are mutually connected to form a rigid vertically-movable skeleton frame by longitudinally-extending top bars b b and by cross-rails c c. 100

Pivotedly connected to the four upper corners of the vertically-movable frames are

four levers G G, which respectively rest upon four diagonal braces d d, secured to each corner of the frame-work D. These braces d d constitute fixed fulcra upon which the levers 5 G G respectively oscillate in a vertical direction. The four levers G G are all of the same length, and their respective fulcra are equidistant from the ends of the several levers. The four levers G G extend in a substantially 10 horizontal plane toward the center of the frame-work D, so that their free ends are in close proximity.

Pivoted at the rear lower part of frame-work D is a treadle H, which extends beneath 15 the free ends of the levers G and projects out beyond the front side of the machine so as to be within convenient reach of the attendant. The free ends of the several levers G are respectively connected to the treadle by chains 20 e e. Consequently when the free end of the treadle is depressed the free ends of the levers G are lowered, and consequently the vertically-movable frame is elevated. When the foot is removed from the treadle, the vertically-movable frame resumes its normal lowermost position.

In order to retain the vertically-movable frame in its elevated position, the treadle is provided with a lateral lip f, which co-operates 30 with a fixed rack g on the frame-work D, the treadle having a sufficient lateral movement to permit of the engagement and disengagement of the lip and the racks. In this manner the vertically-movable frame 35 may be raised and lowered vertically in a straight line, as desired.

Mounted on the vertically-movable frame is a traveling carriage I, which is capable of being reciprocated in a straight line on said 40 frame. On each side the carriage I is provided on its under side with shoes h h, (which may be replaced by rollers i i, if desired, both being shown in the drawings,) which rest and slide upon rails j j on the outer top bars b b of the vertically-movable frame. To maintain the proper relative position between the carriage and frame, the carriage has a downwardly-projecting guide-flange k, which rests and slides in a grooved 45 way l, formed above the central bar b of the vertically-movable frame. Mounted on the carriage is a rotary bed-plate J, which turns freely in a horizontal plane and in either direction around a central spindle m, secured 50 to the carriage. Upon this rotary plate the leather to be treated is placed.

The vertically-movable frame, the reciprocating carriage, and the rotary plate constitute the universally-movable leather-carrying 60 table or bed. By the described construction every portion of the leather placed on the plate J can be brought beneath any given point above the plate without shifting the position of the leather, provided the leather 65 does not project beyond the edges of the plate, the plate, however, being easily made large enough to accommodate any size of leather.

The rotary plate is rotated on the carriage I by the attendant by means of hand-knobs n n on the plate.

The padded roller A, which applies the solution to the surface of the leather on the leather-carrying plate, is itself carried on one end of a shaft K, which is journaled in fixed bearings o o, supported by depending brackets p p, secured to the frame-work D. The padded roller is rotated in the direction indicated by the arrow l by means of a driving-belt q or equivalent means, which passes over a grooved pulley r on the outer end of shaft 75 K and over guide-pulleys s s on the fixed frame-work D. The padding of roller A is composed of felt or other suitable absorbing material.

Above the padded roller there is mounted 80 upon the frame-work the supply tank or vat B, having an outlet t at its bottom, from which leads a horizontal conducting discharge-pipe L immediately above the padded roller. The discharge-pipe has a series of discharging, 85 perforations u u above the padded roller, so that the solution from the tank or vat is distributed evenly and uniformly upon the padded roller throughout its length.

An agitator M is provided within the tank 90 or vat for the purpose of keeping the solution within it homogeneous. This agitator consists of a series of revolving blades v v, carried by a vertical rotating arbor w within the vat or tank. The blades v v rotate in a horizontal plane just above the discharge-outlet t, so that the solution is acted upon just before leaving the vat, thus securing the homogeneity of the solution when supplied to the padded roller A. The arbor w is rotated from 95 the shaft K, through the instrumentality of grooved pulleys x x on the arbor and shaft, respectively, an intermediate drive-belt y, and intermediate guide grooved pulleys z z.

In front of and behind the padded roller A are splasher-shields N, against the inner surface of which any surplus solution conveyed to the roller is thrown. The front shield receives by far the greater part of such surplus solution, (since the roller comes in contact 105 with the leather before any of the solution can be thrown off against the rear splasher,) and consequently a drain-trough O is provided along the lower inner edge of the front shield N. Any solution collecting in the trough is 110 carried off by a downwardly-inclining pipe P, which extends backward beyond the frame-work D, out of the way.

In using the machine the leather is first placed on the upper surface of the universally-moving leather-carrying table or bed C when the latter is in its lowered position. There is then sufficient space between the surface of bed-plate J and the padded roller A to enable the leather to be passed beneath the 120 roller. The treadle is then depressed, thus elevating the table or bed C and bringing the leather thereon in contact with the rotating padded roller. The pressure of the roller 125

on the leather can be varied by means of the extent of depression of the treadle.

During the operation of the machine the padded roller rotates in a predetermined position by reason of the fact that its bearings are normally fixed or stationary, so that it forms a surface against which the leather can be pressed with any desired degree of pressure by the upward movement of the bed-plate.

10 The attendant then moves the bed-plate J in and out and rotates the same, thus bringing every portion of the leather into contact with the padded roller, so that the solution is applied to every portion of the surface of the leather.

15 The several movements of the bed-plate in connection with the padded roller enable the solution to be thoroughly and uniformly rubbed in. Every portion of the leather can 20 be held in contact with the roller a sufficiently long time, or may be presented to the roller a sufficient number of times to effectually rub the solution into the leather.

In order that all the leather may be acted 25 upon by the padded roller, it is only essential that the carriage I should have a reciprocating movement equal to the radius of the circular bed-plate J. As shown in the drawings, when the carriage is pushed back to its limit 30 the center of the plate J is beneath the padded roller, and when the carriage is drawn forward the proper distance the outer margin of plate J (within the operating-knobs n n) is beneath the padded roller. To permit the forward movement of the carriage I to a sufficient extent, the bars b b b of the vertically- 35 movable frame and the rails j j and way l thereon are extended in front of the machine, as shown. The carriage can, if desired, be moved forward, so that the bed-plate J will be entirely clear of the padded roller to facilitate placing the leather in position. Since the padded roller A rotates constantly in one direction, its friction upon the leather lying 40 on the bed-plate J tends to slide the carriage I in a direction determined by the direction of rotation of the roller A. Since, as illustrated in the drawings, the roller rotates in the direction indicated by the arrow 1, the carriage l is acted upon by a force which 45 would move it in a direction indicated by the arrow 2, or toward the rear of the machine. This action of the padded roller on the bed-plate J and carriage I is objectionable, since it interferes with the ready and easy manipulation of the bed-plate and carriage by the attendant. Mechanism is therefore added for neutralizing this action of the padded roller. This neutralizing mechanism, as shown, consists in counter-weights Q Q, which when not 50 counteracted by the padded roller move the carriage I forward, or in a direction opposite to that in which the carriage is moved by the padded roller. These counter-weights are arranged on opposite sides of the carriage and 55 connected to the rear end of the carriage by

means of cords or chains R R, which pass over and between intermediate guide-pulleys S S. Two guide-pulleys S S are provided on each side for each cord, so that if the carriage 70 is moved so far forward that its rear end passes in front of the pulleys S S the cord R will be held in position and not be chafed, worn, or entangled on any part of the fixed frame-work.

75 By the employment of this machine the blacked surface of leather may be treated with the seasoning solution in an effective, uniform, rapid, thorough, and economical manner, and the leather can then be glazed 80 in a glazing-machine without removing the blacking, and can be given a high and brilliant polish.

I claim as my invention—

1. In a machine for applying a seasoning 85 solution to the surface of leather, a universally-movable leather-carrying table or bed the universal movements of which enable it to be raised and lowered to be moved longitudinally and to be moved laterally, in combination with a power-driven rotating padded roller journaled in fixed bearings and located above said table or bed for applying a seasoning solution to and rubbing it in the surface of leather on said table or bed, the vertical movement of said table or bed enabling the leather thereon to be pressed against said roller, a source of supply for the seasoning solution, and means for conducting it therefrom to said padded roller, substantially as set forth. 95

2. A rotating roller for applying a liquid solution to the surface of leather, the rotating shaft of said roller, and a leather-carrying table or bed co-operating with said roller, in combination with a supply-tank for holding the 105 solution and feeding it to the said roller, a rotating arbor within said tank, agitating-blades on said arbor, and mechanism intermediate between said shaft and arbor whereby the arbor is rotated by the shaft, substantially as 110 set forth.

3. In a leather-finishing machine, a rotating padded roller for applying a liquid solution to the surface of leather, a leather-carrying table or bed beneath said roller and co-operating therewith, and a feed-tank for supplying a liquid solution directly to said roller, in combination with a splasher-shield above and out of contact with said table or bed and co-operating with said roller to receive any 115 surplus solution from the same, and a drip-trough along the lower edge of said shield and above said table which receives the surplus solution from the shield and prevents it from falling onto said table or the leather thereon, 120 substantially as set forth.

4. A universally-movable leather-carrying table or bed consisting of a vertically-movable frame, a reciprocating carriage sliding on said frame, and a rotary leather-holding 130 plate turning on said carriage, in combination with means co-operating with said table or

bed for applying a liquid solution to the surface of leather upon the same, substantially as set forth.

5. The reciprocating leather-carrying carriage and supporting-plate and a rotating roller which acts frictionally upon the surface of the leather on said carriage and plate, in combination with counter-weights connected to said carriage and acting to move

10 the same in a direction opposite to that in

which the tangential portion of said roller is moving, substantially as set forth.

In witness whereof I have hereunto signed my name in the presence of two subscribing witnesses.

GEORGE W. LENNOX.
